CONTAINERS AND CLOSURE MEMBERS THEREFOR

Russell D. Rhodes, Kansas City, Kans.

Application August 27, 1956, Serial No. 606,422

4 Claims. (Cl. 222—425)

My invention relates to containers and closure members therefor, and particularly to a container that has a closure member telescopically related thereto.

More specifically, my invention comprises a closure member that is adapted to be applied to a standard container such as a standard glass jar, which closure member is made of transparent flexible material so that it will slidably engage the body portion of the jar or similar container with a gripping engagement due to the flexibility of the material. The flexible material is preferably a plastic that is of such a character that it has sufficient resiliency to grip the wall portion of the container with which the closure member is associated, the character of the plastic material at present preferred being clear acrylic resin. Preferably the closure member is integrally molded, although if found desirable, the body portion and the end wall thereof may be made of separate pieces suitably secured together in a well known manner by adhesive or heating, depending upon the character of the plastic material used.

It is an important purpose of my invention to provide a container and closure member that are so related that when the closure member is in one of its limiting positions it will hold the closure member in sealing engagement with the container, while, when it is in the other limiting position in which the closure member is extended endwise beyond the container, the contents of the container can be poured or otherwise passed into the extended closure member so that the contents will thus become accessible through a suitable opening provided therefor in the closure member.

The closure member is telescopically related to the container, which, in its standard form, is open at one end thereof, the closure member having a closed end wall and a cylindrical side wall that extends from the closed end wall and has an access opening therein that is in the form of a wide gap extending from adjacent the closed end wall to the open end of the closure member. It is a purpose of my invention to provide means on said cylindrical side wall that slidably engages the cylindrical body portion of the jar or similar container, and which is located adjacent the open end of the closure member, that grippingly engages the container. Containers of the character with which my closure member is used usually have a flange and gasket holding means thereon adjacent the open end thereof and have a convex wall portion at the periphery of the closed end wall where the closed end wall joins the side wall of the container.

The means that grippingly engages the side wall of the container that is on the closure member is of such a character that it is adapted to engage or snap around said convexly curved end wall to hold the gasket that is provided on the gasket holding means on the jar in engagement with the closed end wall of the closure member to seal the container. In order that this can be accomplished, a new type of sealing means is provided in the form of a gasket that is annular in character and which projects endwise beyond the open end of the jar

2

or similar container when it is in place so that the compressible gasket member will engage the closed end wall of the closure member to provide the seal between the closed member and the container, and the open end of the closure member is provided with resilient means to assure that the gripping means will firmly engage said convex wall portion.

Other objects and advantages of my invention will appear in the description of the drawings proceeds. I desire to have it understood, however, that I do not intend to limit myself to the particular details shown or described, except as defined in the claims.

In the drawings:

Fig. 1 is a vertical sectional view through the container and closure member made in accordance with my invention, in container sealing position.

Fig. 2 is a similar view showing the closure member moved out of closing position.

Fig. 3 is a side elevation of the closure member partly broken away.

Fig. 4 is a section taken on the line 4—4 of Fig. 3.

Fig. 5 is a fragmentary longitudinal sectional view through the container and the closure member in an extended position, and

Fig. 6 is a fragmentary section, on an enlarged scale, taken substantially on the line 6—6 of Fig. 4.

Referring in detail to the drawings, the container to which my invention is applied is a standard glass jar having the cylindrical side wall portion 6, a closed end wall 7, an open mouth 8, an annular flange 9 and gasket retaining means 10 adjacent the mouth or open end 8 thereof. As is customary in containers of this character, the end wall 7 has a peripheral convexly curved portion 11, that joins it with the side wall 6.

In carrying out my invention I provide the container with a compressible annular gasket member 12 adjacent the mouth 8 thereof, which is provided with an annular groove that receives the retaining means 10 and which has inclined wall portions 13 and 14 that are of a conical character and which terminate in an apex or edge portion 15 to thus project the portion 16 of said gasket beyond the end edge 8 of the container. Said compressible gasket member 12 also seats against the flange 9, and preferably has an annular lip 26 overlapping the end edge of the open mouth 8 to provide a seal between said gasket 12 and the container.

My improved closure member is provided with an end wall 17 and a side wall 18. The side wall 18 is cylindrical in character and joins the end wall 17 slightly inwardly from the peripheral edge 19 thereof, to thus provide a narrow flange on the closed end of the closure member. The cylindrical wall portion 18 extends only partially around the container to which it is applied, having edge portions 20 that extend longitudinally of said side wall portion 18 and are widely spaced from each other to provide a wide gap 21 between said edges, whereby an access opening is provided into the closure member when it is extended beyond the mouth 8 of the container, full access thereto being obtained when it is moved to the limiting position extended beyond said mouth 8, as shown in Fig. 5. The end wall 17 and the cylindrical side wall portion 18 are preferably made of a unitary piece of molded plastic material, such as clear acrylic resin, although any clear plastic that is of such a character that the wall portions 18 can flex outwardly from the position shown in Fig. 1 to that shown in Fig. 2 can be used. The open end edge of the closure member is provided adjacent thereto with a plurality of inwardly extending projections 22, which are also preferably molded integrally with the wall portion 18. Said projections are preferably located adjacent each of the edges 20 and at a point midway between the edges 20, as shown

in Fig. 4, so as to provide a three point engagement of the closure member with the container.

When the parts are in the position shown in Fig. 1 the resiliency of the closure member will cause the projections 22 to grip the convex peripheral wall 11 of the end walls 7 and the closure member is of such length that when such engagement between the projections 22 and the convex wall portion 11 occurs the gasket member 12 will be compressed between the flange 9 and the end wall 17, and the peripheral edge of the mouth 3 and said end wall, thus sealing the contents of the container against access of air, moisture, or foreign matter thereto. Preferably a spring wire 27 is mounted in a groove 28 and extends circumferentially of the side wall 18 at its open end edge 29 to guard against spreading of the wall portion 18 and assure that gripping engagement of the projections 22 with the convex end wall portion 11 will be maintained. The spring wire 27 is preferably retained in the groove 28 by applying heat and pressure to the material of the side wall 18 at its peripheral edge 29 to form retaining beads 30 at spaced intervals along said edge.

When the closure member is moved from the position shown in Fig. 1 into a position such that the projections 22 engage the cylindrical wall portion 6 of the container, the wall portion 18 will be sprung slightly outwardly, as shown in Fig. 2, and this outwardly sprung position of the wall portion 18 will continue until the projections 22 pass along the wall portion 23 of the container, whereupon the projections will seat in the annular recess 24 adjacent the flange 9, as shown in Fig. 5.

One of the uses of the container is illustrated in Fig. 5, in which various objects 25 stored in the container have been allowed to roll or flow outwardly into the extended closure member so that these can be reached through the access opening 21 and a desired article removed therefrom. While fastening elements are shown as being the contents of the container in Fig. 5, any suitable small parts, or any suitable loose, or even fluid material, can be stored in the container and can be made accessible by extending the closure member endwise, as shown in Fig. 5, and sealed within the container against leakage by moving the closure member to the sealing position shown in Fig. 1. The closure member can be moved between the position shown in Fig. 1 and that shown in Fig. 5, and vice versa, by merely pushing on the flange 19 or the end wall 17 with the fingers of the hand in which the container and closure member are being held, thus leaving the other hand free to remove material, such as the articles 25, from the extended closure member, which, when in its extended position, forms a tray-like holding means for the articles that are poured or flowed into the same from the container by suitably tilting the container slightly upwardly relative to the closure member with the closure member in its extended position.

What I claim is:

1. The combination with a container having a cylindrical body portion open at one end thereof having a flange and gasket holding means adjacent said open end and an end wall having a convexly curved peripheral portion, of a closure member telescopically related to said container open at one end thereof having a closed end wall and a cylindrical side wall extending from said closed

end wall of said closure member, an annular gasket mounted on said gasket holding means and projecting endwise beyond the open end of said container and means on said cylindrical side wall engaging said convexly curved end wall portion to hold said gasket in sealing engagement with the end wall of said closure member, said cylindrical side wall having an access opening therein.

2. The combination with a container having a cylindrical body portion open at one end thereof having a flange and gasket holding means adjacent said open end and an end wall having a convexly curved peripheral portion, of a closure member telescopically related to said container open at one end thereof having a closed end wall and a cylindrical side wall extending from said closed end wall of said closure member, an annular gasket mounted on said gasket holding means and projecting endwise beyond the open end of said container and means on said cylindrical side wall engaging said convexly curved end wall portion to hold said gasket in sealing engagement with the end wall of said closure member, and adapted to engage said flange to limit opening movement of said closure member.

3. The combination with a container having a cylindrical body portion open at one end thereof having a flange and gasket holding means adjacent said open end and an end wall having a convexly curved peripheral portion, of a closure member telescopically related to said container open at one end thereof having a closed end wall and a cylindrical flexible side wall extending from said closed end wall thereof and having a wide gap therein extending from adjacent said closed end wall to the open end of said closure member, an annular gasket mounted on said gasket holding means and projecting endwise beyond the open end of said container and means on said cylindrical side wall engaging said convexly curved end wall portion to hold said gasket in sealing engagement with the end wall of said closure member.

4. The combination with a container having a cylindrical body portion open at one end thereof having a flange and gasket holding means adjacent said open end and an end wall having a convexly curved peripheral portion, of a closure member telescopically related to said container open at one end thereof having a closed end wall and a cylindrical flexible side wall extending from said closed end wall thereof and having a wide gap therein extending from adjacent said closed end wall to the open end of said closure member, an annular gasket mounted on said gasket holding means and projecting endwise beyond the open end of said container and circumferentially spaced inwardly directed projections on said cylindrical side wall engaging said convexly curved end wall portion to hold said gasket in sealing engagement with the end wall of said closure member.
